CLAIM

The ornamental design for a soft foam insert for a combined baseball and card storage tray, as shown and described.

DESCRIPTION

FIG. 1 is an enlarged perspective view of a soft foam insert for a combined baseball and card storage tray showing my new design;

FIG. 2 is a top plan view thereof;

FIG. 3 is a bottom plan view thereof;

FIG. 4 is a front elevational view thereof, the rear elevational view is a mirror image thereof; and,

FIG. 5 is a side elevational view thereof, the opposite side is a mirror image.

FIG. 1

FIG. 2

FIG. 3

FIG. 4

FIG. 5
